UNITED STATES PATENT OFFICE.

JOHN G. SNYDER, OF ALTOONA, PENNSYLVANIA.

METALLIC RAILWAY-TIE.

939,343.

Specification of Letters Patent.

Patented Nov. 9, 1909.

Application filed July 6, 1909. Serial No. 506,210.

To all whom it may concern:

Be it known that I, JOHN G. SNYDER, a citizen of the United States, residing at Altoona, in the county of Blair and State of Pennsylvania, have invented new and useful Improvements in Metallic Railway-Ties, of which the following is a specification.

My invention relates to improvements in railway ties made of a metal casing formed by turning the longer ends of a T beam downwardly and inwardly toward the stem of the T, thereby forming a casing, and having a central support. The ends may be brought toward the stem above the foot of the T or below. The material used for constructing this railway tie may be rigid or resilient, but preferably the latter.

The object of my invention is to make a tie which will have the advantages of a wooden tie, but none of the disadvantages. The resiliency, if desired, can be obtained by using a spring material for making this casing which, by reason of its shape, will necessarily afford a resilient support.

With this and other objects in view, reference is made to the accompanying drawing, in which—

Figure 1 is a plan of a railway tie showing the openings for retaining the fastening clips in adjusted position. Figs. 2, 3 and 4 are different modifications of the casing, all of which embody the essential features of my invention. Fig. 5 is a detailed view in section, showing means of securing the rail to the casing. Fig. 6 is an enlarged view of one of the clips which holds the rail in place. Fig. 7 is a section of the tie showing the filling.

Similar letters of reference are used on similar parts throughout the several views.

The tie is made preferably from a T beam having elongated arms which are turned downwardly and inwardly as shown at "D" Fig. 2, and "D'" Fig. 3 and "D''" Fig. 4. The stem of the T "B" is preferably located in the center, but may be on either side of the same or at an angle to the general extent of the casing. The foot of the T "C" may be above or below the ends "D", and the bend in the sides "D" may be of any shape desired. The ends of the sides "D" may abut against the stem of the T "B", or they may be free. The base of the T "C" may be smooth or it may have a portion turned down to get a firmer grip in the ballast.

Such projections are shown at "x x" Fig. 3. The tie has slots "g g" communicating with the slot "h" formed on opposite sides of the rail seat so that a clip "E" can be fastened in place by means of the bolt "e" 60 passing through the casing and a slot "d" in the clip. The downward turned flange "a" of the clip "E" is adapted to engage the shoulders of the slots "g g". By placing the clip in different slots "g g" the gage of 65 the track can be changed as may be needed by reason of wear on the inner portion of the rail. The bolt is preferably formed with the flattened shank or some other means for preventing rotation, and the head of the 70 bolt is adapted to pass through the large slot "g" and slide into the small slot "h". After the clip is put in position and a washer placed over the bolt, the nut is screwed down securely thereby holding the 75 clip and rail absolutely in place.

In Fig. 3 the arms of the T are curved more sharply than in Fig. 2, and are brought directly down to the base of the T. This forms inclined sides which run directly to 80 the base of the T, thereby facilitating the tamping of the ballast around the tie and giving it a good bed for support.

Fig. 4 shows a form of tie in which the central support is entirely inclosed within 85 the casing formed by the downward turned arms of the T. This is intended to give the necessary elasticity to the tie and the central support will limit the movement allowed, thereby giving it the necessary elasticity and 90 at the same time the strength to resist heavy loads, and also to avoid any springing of the sides beyond the co-efficient of elasticity. This form also has the additional advantage of not having an obstruction at the bottom 95 which might interfere with the tamping of the ballast around the tie. The lower edges of the casing may be roughened in any manner to avoid slipping through the ballast. While the casing is preferably open wherever it is of advantage, I provide a resilient 100 filling for the same.

With this and other objects in view, I claim as follows:—

1. A metallic railway tie consisting of a 105 casing having downwardly and inwardly turned sides and a support substantially central thereof, extending downward from the top in a longitudinal direction, and means to secure a rail to the casing.

110

2. A metallic railway tie formed by turning the longer ends of a T beam downwardly and inwardly toward the web of the beam, and means to secure a rail to said tie.
- 5 3. A metallic railway tie formed by turning the longer ends of a T beam downwardly and inwardly toward the web, means to secure a rail to said tie, and a filling for said tie.
- 10 4. The combination of a metallic railway tie formed by turning the longer ends of a T beam downwardly and inwardly toward the web, a clip for holding the rail in place, means in the tie for holding the clip in ad-

justed position, and means for securing the 15 clip to the casing.

5. A metallic railway tie formed by turning the longer ends of a T beam downwardly and inwardly toward the web of the beam, slots with projections therein cut in said tie, 20 a clip for holding the rail in place having a downward turned flange adapted to engage the projections in said slots, and means for securing the clip to the tie.

JOHN G. SNYDER.
